FUR CUTTING MACHINE

Oscar M. Dean, Sioux City, Iowa

Application January 16, 1935, Serial No. 2,111

37 Claims. (Cl. 164—50)

My present invention relates generally to the art of cutting fur bearing hides, or more particularly to the art of notching the edges of fur bearing hides which are to be sewed together, and primarily has for its object to provide a machine embodying novel mechanisms for performing this function.

It has been discovered in the fur garment industry that the line of stitching between two skins can be fairly well concealed by providing the edges of the skins with interfitting notches and sewing the skins together along the edges of these notches. It has also been found difficult to cut fur bearing hides along any desired line without objectionably severing hairs of the hide during the cutting process. In Patent 1,895,025 issued January 24, 1933, I disclosed a novel method of cutting fur bearing hides along a desired line without objectionably severing hairs, the particular line disclosed being the desired notched or zig-zag line. The mechanisms disclosed in that patent as an example of means adaptable for performing the method included a slender cutting element triangular in cross section, means to reciprocate the element, means to advance the hide past the element, and means to translate the element back and forth across the path of travel of the hide in timed relation to the speed of advancement of hide to cause the individual cuts or punctures formed by the element in the hide to conjointly form a continuous zig-zag or notched-line cut in the hide.

In its more detailed nature, my present invention seeks to provide a novel fur cutting machine embodying certain new and useful improvements over the mechanisms disclosed in my patent above referred to and including a novel slender, flat blade cutting element; novel means for reciprocating the element; novel means for translating the element back and forth across the line of advancement of the hide; and novel means for changing the position of the element at the termination of movement of translation in each direction so that the flat of the blade will be presented in the line of cut at all times, thus avoiding mutilation of the hide along either side of the line of cut.

With the above and other objects in view which will more fully appear, the nature of the invention will be more clearly understood by following the description, the appended claims, and the several views illustrated in the accompanying drawings.

55 In the drawings:—

Figure 1 is a left side elevation, the left side frame half being removed.

Figure 2 is a front elevation.

Figure 3 is a detail vertical longitudinal section through the axis of the slide or carriage 5 and the cutting element carrying bar reciprocably supported and translated thereby.

Figure 4 is a horizontal section taken on the line 4—4 on Figure 1.

Figure 5 is a horizontal section taken on the line 5—5 on Figure 1.

Figure 6 is a vertical cross section taken on the line 6—6 on Figure 1.

Figure 7 is a vertical cross section taken on the line 7—7 on Figure 1.

Figure 8 is a detail horizontal section taken on the line 8—8 on Figure 1.

Figure 9 is a diagrammatic plan view illustrating a section of hide passing over the supporting plate and the formation of a continuous or zig-zag notched-line cut therein.

Figure 10 is a diagrammatic plan view illustrating the manner in which the hide and the cutting element move relatively to cause the cutting element to form a continuous zig-zag or notched-line cut.

Figure 11 is a detail vertical cross section illustrating the cutting element in the act of piercing or penetrating the hide and deflecting but not cutting hairs thereof.

In the drawings in which like numerals of reference indicate like parts in all the figures, I have disclosed a frame or casing for housing the mechanisms of the machine and comprising complementary half members 5 and 6 removably secured together by screws 7. The half members together form a base 8, a standard 9, an overhanging arm 10, and a front head portion 11 for accommodating the various mechanisms of the machine.

Aside from one feed roller and its driving pinion, all of the mechanisms of my improved machine are supported in the half member 5 and are accessible by removal of the half member 6 and for this reason the frame section 5 is provided with horizontal shaft bearings 12, vertical shaft bearings 13, and horizontal slide guides 14.

A main drive shaft 15 is rotatably supported in the bearings 12 and projects from the rear end of the frame where it is equipped with a driving pulley 16 and a handwheel 17. Within the frame, the shaft 15 also carries a worm 18 which meshes with a worm wheel 19 mounted on a cross shaft 20 suitably journaled in the frame halves, and the shaft 20 also carries a worm 21 which

meshes with a worm 22 mounted on a shaft 23 rotatable in the vertical bearings 13.

At its lower end the shaft 23 carries another worm 24 which meshes with a worm 25 mounted 5 on the drive shaft 26 which is rotatable in bearings 27 provided therefor in the frame half 5. At its front end the drive shaft 26 projects into the front head portion 11 where it is equipped 10 with a driver pinion 28, the purpose of which will become apparent as the description progresses.

A cutting element supporting and translating slide or carriage 29 is supported in the slide guides 14 and is movable back and forth in said guides for imparting back and forth or reciprocatory movement of translation to the cutting element 15 in a manner and for a purpose later to be described. The carriage 29 is retained in the guides 14 by removable plates 30 and is equipped at its front end with upper and lower bearing extensions 31, and at its rear end with two diametrically oppositely disposed cam ears 32 providing an axially extending cam portion in the nature of a crown cam having the cam surfaces thereof which form the projections and depressions or 25 notches bearing approximately 90° angular relation.

The ears 32 of the cam portion extending axially from the rear end of the slide carriage 29 are adapted to engage and cooperate with similar 30 ears 33 or crown cam portions projecting from a spur gear rotor 34 which is freely rotatable about the axis of the shaft 15 and adapted to be driven by the gear 35 secured upon the drive shaft 26. It will be understood that by reason of 35 the worm gear connections hereinbefore described the relatively rapid rotation of the main shaft 15 will be transmitted in the form of very slow rotation to the drive shaft 26 and the crown cam portion 33 and hide advancing pinion 28 to 40 which it imparts motion.

The slide carriage 29 affords rotative bearing, as at 36, for a shaft section 37 which is axially aligned with the main shaft 15, and by reason of the spline connection between these shaft sections 15 and 37 they in effect constitute a single 45 extensible shaft, the portion 37 being capable of longitudinal movement back and forth with the slide 29. At its front end the shaft section 37 projects from the carriage 29 and is equipped 50 with a crank disc 38 having an off center anti-friction crank roller 39 which operates in a cross slot in a slide block 40 which supports and imparts vertical or axial reciprocation to the cutting element carrying bar 41. The bar 41 is 55 free to rotate about its axis in the block 40 but is held against longitudinal movement relative to the block by collars 42.

At its lower end the cutter bar is provided with any suitable form of clutch in which the cutter element 43 may be removably secured. In this 60 disclosure the hide cutting element is in the nature of a flat, slender, or narrow element having two cutting edges merging in a central piercing or penetrating point.

The cutter bar 41 has ordinary reciprocable 65 bearing in the lower carriage extension 31 but in the companion or upper extension 31 said bar passes through a bearing sleeve 44 which is held against longitudinal movement relative to the carriage by a collar 45 encircling and secured 70 to its lower end by an enlargement just above the upper extension 31 and which is equipped with two diametrically oppositely disposed stop lugs 46 as best shown in Figures 3 and 8 of the drawings. The sleeve extends a considerable dis-

tance above the enlargement and the cutter bar accommodating opening in this extended portion of the sleeve is squared or otherwise non-circular to cooperate with a non-circular portion 47 of the cutter bar in permitting said cutter bar 5 to reciprocate longitudinally within the sleeve but assuring rotation of said sleeve about its axis with the cutter bar.

An abutment collar 48 is secured to the upper end of the vertical extension of the sleeve 44 and beneath this collar a coil spring 49 encircles the sleeve extension and has its respective ends so engaged with pins 50 projecting from said collar and a winding ratchet collar 51 encircling the sleeve extension below the spring as to cause the spring to constantly tend to rotate the sleeve 44 and the cutter bar 41 about their common axis. See Figures 3 and 4.

The winding ratchet collar 51 is equipped with four teeth disposed in equidistantly spaced relation about the axis of the collar and opposed, at opposite sides, as shown in Figures 1 and 4 of the drawings, by a pair of oppositely effective spring energy holding and restoring fingers 52 which are pivotally supported as at 53 upon the 20 rearmost slide guide 14 and held against the opposite edges of the ratchet collar by a retractile spring 54.

A stop and release member 55 is pivotally supported upon the upper bearing extension 31 of the slide 29 in position for having the stop releasing fingers 56 thereof alternately engage with the stop lugs 46 projecting from the enlargement of the sleeve 44. The member 55 includes an actuator arm extension 57 which projects 30 between and is adapted to engage one or another of a pair of spaced adjustable abutment stops 58 at the end of movement of translation of the slide or carriage 29 in a given direction. It will be noted that while the stop lugs 46 are 35 diametrically oppositely disposed the fingers 56 of the stop and release member 55 bear 90° angular relation. By reference to Figure 8 of the drawings, it will be understood that as the carriage 29 advances forwardly in the direction of the arrow, and has approximately completed its movement in that direction, the actuator arm 57 40 will engage the foremost abutment 58 and the position of the stop and release fingers 56 shown in full lines will be changed to the position shown 45 in dotted line thus releasing the then held or stopped lug 46 and permitting it, the sleeve 44 and the cutter bar 41, to rotate 90° about their common axis in clockwise direction and then to be stopped by the remaining finger 56 which has been projected into the path of movement 50 of the lug 46 as shown in dotted lines in Figure 8. At the conclusion of movement of the carriage 29 in the opposite direction the arm 57 will engage the rearmost abutment 58 and re- 55 verse the position of the fingers 56 or in other words return them to the position illustrated in full lines in Figure 8 thus releasing the lug 46 and permitting the cutter element assembly to turn from the dotted line position to the full 60 line position illustrated in Figure 8.

It will be observed by reference to Figure 4 of the drawings that one or another of the ratchet collar-engaging fingers 52 will always be in engagement with one of the teeth of said collar 70 thus holding the tension stored in the coiled spring 49. It will be apparent also that as the cutter element assembly is rotated 90° about its axis as above described some of the tension stored in the spring 49 will be released in effecting this 75

movement. The spring tension thus lost is restored and the spring always retained at desired efficiency in the following manner. Each time the carriage 29 moves forwardly or rearwardly 5 it carries the cutting element assembly including the ratchet collar 51 with it and as the ratchet collar 51 is moved back and forth between the fingers 52 one or the other of the fingers is always active to impart a degree of rotation to the collar 10 tending to wind or store energy in the spring 49, and this restoration of energy is always sufficient to compensate for losses incident to the rotation of the cutting assembly about its axis.

The frame halves 5 and 6 have open portions 15 at the front which cooperate to form an opening 59 through which access may be had to the cutting element assembly. See Figures 1 and 2. The opening 59 is accessible through a removable plate 60.

20 Each of the frame halves 5 and 6, in the front portions thereof which together form the head portion 11, carries a hide advancing or feed roller 61 mounted on a shaft 62 journaled in the respective frame half portion and equipped with 25 a driven gear 63. When the frame halves are assembled as shown in Figure 2 of the drawings, the gears 63 of the respective rollers mesh with a centrally mounted driver gear 64 rotatably supported on the stud shaft 65 secured in the frame half 5, and to this driver gear slow rotation is 30 imparted by the driver pinion 28 hereinbefore referred to. In this manner the feed rollers 61 are rotated slowly and in constantly timed relation to the sliding or translatory movement of 35 the carriage 29 and the hide cutting assembly movable therewith.

A brake cam 66 is fixed to or formed integral with the crown cam and gear 33, 34 and includes 40 two diametrically oppositely disposed high points or maximum brake applying surfaces as shown in Figures 1 and 7 of the drawings. A brake arm 68 is pivotally supported at 69 on the frame half 5 and includes an overhanging flange portion 70 and a brake shoe 71 for cooperating with 45 the cam surfaces. The arm 68 is pressed against the cam by an adjustable compression spring 72 and exerts a pressure thereon which serves to govern the rotation of the cam portion and prevent accelerated relative movement of the parts 50 at any time. As the high points of the cam portions 32 and 33 are passing, at which time the greatest tendency for accelerated movement of the cam and gear unit 33, 34 or the carriage 29 occurs, the brake arm will then be in engagement 55 with one of the high points of the cam and will therefore be exerting its maximum braking efficiency in order to effectively overcome this tendency.

The hide advancing or feed rollers 61 are 60 opposed by a work plate 73 supported upon a rocker arm 74 pivoted as at 75 to the frame. The plate 73 is tiltably supported on said arm, being pivotally supported thereon at 76 and 77, the pivots being arranged with their axes in right angular 65 relation so as to in effect form a universal tilt mounting for said plate. A compression spring 78 engages the arm 74 and yieldably presses the plate 73 and the hide supported thereon against the rollers 61. A push rod 79 attached to a suitable treadle (not shown) may be utilized to 70 separate the plate from the rollers for the purpose of insertion and removal of a hide. The plate is provided with a longitudinal opening 80 disposed between the rollers 61 as shown in Figures 9 and 11, said opening being of a shape and

size for accommodating the translatory movement of the cutting element and also for permitting freedom of hairs of the hide in the cutting area so that they may be deflected by the cutting element.

Brackets 81 are secured to the carriage 29 and rods 82 extend from the brackets and enter receiving sockets 83 in the foremost slide guides 14. The rods 82 are encircled by the coils of compression springs 84 which are interposed between 10 the brackets 81 and the bearing 14 and serve always to urge the carriage 29 rearwardly thus 15 constantly holding the crown gear portion 32 thereof in engagement with the companion cam equipment 33.

At its upper end the cutter bar 41 is extended through a longitudinal opening in the frame and equipped with a knurled head 85. This equipment makes it possible to manually manipulate the cutter bar to hold it stationary while manipulating the cutting element securing clutch, to 20 manually change the angular position of the element, or to manually restore tension in the spring in case of any emergent condition of use.

In operation the rapid rotation imparted to the 25 shaft 15 will be transmitted in the form of rapid vertical or axial reciprocation to the cutter bar 41 by the disc 38 and roller 39. The rapid rotation of the shaft 15 will likewise be transmitted in the form of relatively slow rotation to the 30 shaft 26, in constantly timed relation to the cam portion 33 and hide advancing rollers 61 driven therefrom. It will be obvious also that by reason of the slow rotation of the cam portion 33 and its 35 engagement with the cam portion 32 the carriage 29 will be reciprocated or translated slowly back and forth moving the reciprocating cutting element slowly back and forth across the path of the advancing hide.

The result of slowly advancing the hide and 40 slowly translating the cutting element back and forth across the path of advancement of the hide in constantly timed relation, is the formation of a continuous zig-zag or notched-line cut, each zig x and each zag y of such cut being 45 formed by a rapid succession of individual narrow cuts formed by the cutting element as illustrated in Figures 9 and 10. In forming this cut the flat of the narrow cutting element always 50 alines with the line of cut so as to assure a smooth edge cut. This is made possible because any given unit or distance of hide advancement is 55 attended by a like unit or distance of translatory movement of the cutting element and consequently the piercing or penetrating point of the flat cutting element will always strike the hide in the desired line of cut as shown in Figure 10, and at the completion of the succession of cuts forming each zig or zag, and while the cutting element is elevated out of contact with the hide, 60 the element is rotated 90° about its axis as hereinbefore described so as to aline the flat thereof with the zig or zag next to be cut.

The number of cutting element reciprocations, or in other words the number of successive individual cuts, utilized to form the individual zigs and zags of the continuous line cut may vary but always are relatively narrow so as to enable the narrow element to pass between the hairs deflecting but not cutting the same.

In diagrammatic Figure 10 the heavy dots serve 65 to indicate the individual points of penetration and the crossed light lines therefore illustrate what might be termed units of movement, of advancing movement with respect to the hide, and 70 75

of movement of translation with respect to the cutting element. It will be observed that the points of penetration are spaced apart a distance less than the width or major cross sectional area of the cutting element. Thus positioned a continuous line cut is assured. When the piercing or penetrating points are spaced apart a distance less than half the width of the element as shown in Figure 10, one cutting edge alone of the element will be effective in forming the line cut in a given direction.

In this particular disclosure the cutting assembly is rotated step by step, one-quarter of a turn at a time, always in one direction, and thus, in this particular disclosure, as shown in Figures 9 and 10, a given edge of the element forms a zig, the element is turned 90° about its axis, and the same edge forms a zag upon the completion of which the element is again turned 90° about its axis and the other edge will then be effective to form a zig and a zag in a like manner and so on.

It is of course to be understood that the details of structure and arrangement of parts may be variously changed and modified without departing from the spirit and scope of my invention.

I claim:—

1. In a fur cutting machine, the combination of a narrow flat reciprocating cutting element having two cutting edges merging in a central penetrating point, and means to bring about relative movement between a fur bearing hide and said element to cause the element to successively penetrate the hide at intervals spaced less than the major cross sectional area of said element whereby one or the other of said edges will form a succession of cuts conjointly forming a continuous line cut depending upon the direction of said relative movement.

2. In a machine for cutting fur bearing hide, the combination of a narrow flat reciprocable cutting element having two cutting edges merging in a central penetrating point, means to reciprocate the element to cause it to repeatedly penetrate the hide along the desired line of cut with the flat thereof always presented in the line of cut whereby the individual cuts will conjointly form a continuous smooth edged line cut, means for shifting the relative positions of the hide and the reciprocating cutting element to cause the line cut to follow a zig-zag path, and means to control the position of the cutting element to cause first one of the edges to cut a zig and a zag and then the other edge to cut a zig and a zag.

3. In a machine for cutting fur bearing hide, the combination of a narrow flat reciprocable cutting element having two cutting edges merging in a central penetrating point, means to reciprocate the element to cause it to repeatedly penetrate the hide along the desired line of cut with the flat thereof always presented in the line of cut whereby the individual cuts will conjointly form a continuous smooth edged line cut, means for shifting the relative positions of the hide and the reciprocating cutting element to cause the line cut to follow a zig-zag path, and means to control the position of the cutting element to cause first one of the edges to cut a zig and a zag and then the other edge to cut a zig and a zag, said last named means including devices to cause the cutting element to turn about its axis at the completion of each zig or zag to properly align the flat thereof with the zig or zag next to be cut.

4. In a fur notching machine, the combination of a hide advancing means, a reciprocating nar-

row flat cutting element having two cutting edges merging in a central penetrating point and disposed with the flat thereof presented in angular relation to the direction of advancement of the hide, means to impart translatory movement to the element back and forth across the path of advancement of the hide, and means for altering the angular relation of the element at the conclusion of each back and forth movement thereof to align the flat thereof with the succession of cuts next to be made, said angular relation alteration being effected by rotation of the element about its axis always in the same direction.

5. In a fur notching machine, the combination of a hide advancing means, a reciprocating narrow flat cutting element having a cutting edge and a penetrating point and disposed with the flat thereof presented in 45° angular relation to the direction of advancement of the hide, means to impart translatory movement to the element back and forth across the path of advancement of the hide, and means including a spring and energy storing and releasing means actuated by movement of said element translating means for turning the element 90° about its axis at the conclusion of each back and forth movement thereof.

6. In a fur cutting machine, a slender flat cutting element having a penetrating point, means for supporting the element, means for reciprocating the element in its support, spring means tending to rotate the element about its axis, means to secure the element against rotation, and means for at times releasing said securing means to permit the element to rotate a predetermined degree.

7. In a fur cutting machine, a slender flat cutting element having a penetrating point, means for supporting the element, means for reciprocating the element in its support, spring means tending to rotate the element about its axis, means to secure the element against rotation, means for at times releasing said securing means to permit the element to rotate a predetermined degree, and means for restoring energy in the spring means following each release of said securing means.

8. In a fur cutting machine, a slender flat cutting element having a penetrating point, means for supporting the element, means for reciprocating the element in its support, spring means tending to rotate the element about its axis, means to secure the element against rotation, means to impart translatory movement to the element supporting means back and forth between fixed limits and means active at the end of the translatory movement in each direction for releasing said securing means to permit the element to rotate a predetermined degree.

9. In a fur cutting machine, a slender flat cutting element having a penetrating point, means for supporting the element, means for reciprocating the element in its support, spring means tending to rotate the element about its axis, means to secure the element against rotation, means to impart translatory movement to the element supporting means back and forth between fixed limits, means active at the end of the translatory movement in each direction for releasing said securing means to permit the element to rotate a predetermined degree, and means for restoring tension in the spring following each release of said securing means.

10. In a fur cutting machine, a slender flat cutting element having a penetrating point, means

for supporting the element, means for reciprocating the element in its support, spring means tending to rotate the element about its axis, means to secure the element against rotation, means to impart translatory movement to the element supporting means back and forth between fixed limits, means active at the end of the translatory movement in each direction for releasing said securing means to permit the element to rotate a predetermined degree, and means active during the movement of translation for restoring tension in the spring following each release of said securing means.

11. In a machine for cutting fur bearing hide, the combination of a narrow flat reciprocable cutting element having two cutting edges merging in a central penetrating point, means to reciprocate the element to cause it to repeatedly penetrate the hide along the desired line of cut with the flat thereof always presented in the line of cut whereby the individual cuts will conjointly form a continuous smooth edged line cut, means for shifting the relative positions of the hide and the reciprocating cutting element to cause the line cut to follow a zig-zag path, and means to control the position of the cutting element to cause first one of the edges to cut a zig and a zag and then the other edge to cut a zig and a zag, said last named means including devices to cause the cutting element to turn about its axis at the completion of each zig or zag and while free of contact with the hide to properly align the flat thereof with the zig or zag next to be cut.

12. In a fur cutting machine, a slender flat cutting element having a penetrating point, means for supporting the element, means for reciprocating the element in its support, spring means tending to rotate the element about its axis, means to secure the element against rotation, means for at times releasing said securing means to permit the element to rotate a predetermined degree, and adjustable devices for assuring release of said securing means only when said element is out of contact with the hide.

13. In a fur cutting machine, a slender flat cutting element having a penetrating point, means for supporting the element, means for reciprocating the element in its support, spring means tending to rotate the element about its axis, means to secure the element against rotation, means to impart translatory movement to the element supporting means back and forth between fixed limits, and means active at the end of the translatory movement in each direction for releasing said securing means to permit the element to rotate a predetermined degree and including adjustable devices for assuring release of said securing means only when said element is out of contact with the hide.

14. In a fur cutting machine, a bar carrying a slender flat cutting element having a penetrating point, means for supporting the element for reciprocation along its axis and for rotation about its axis and for translatory movement back and forth, means for reciprocating the element, means for effecting the translatory movement, a stop sleeve rotatable with the bar and having a stop lug, a coil spring encircling the sleeve and having its ends in engagement with the sleeve and a relatively stationary member whereby to tend to rotate the sleeve and the bar, a release and stop finger releasably engaging the stop lug, and means operable during translatory movement of the bar for releasing said finger to permit the bar to rotate about its axis.

15. In a fur cutting machine, a bar carrying a slender flat cutting element having a penetrating point, means for supporting the bar for reciprocation along its axis and for rotation about its axis and for translatory movement back and forth, means for reciprocating the bar, means for effecting the translatory movement, a stop sleeve rotatable with the bar and having a stop lug, a coil spring encircling the sleeve and having its ends in engagement with the sleeve and a relatively stationary member whereby to tend to rotate the sleeve and the bar, a release and stop finger releasably engaging the stop lug and having a projecting actuator arm, and an adjustable actuator abutment engageable by said arm during translatory movement of the bar for effecting release of said finger to permit the bar to rotate about its axis.

16. In a fur cutting machine, a bar carrying a slender flat cutting element having a penetrating point, means for supporting the bar for reciprocation along its axis and for rotation about its axis and for translatory movement back and forth, means for reciprocating the bar, means for effecting the translatory movement, a stop sleeve rotatable with the bar and having a stop lug, a coil spring encircling the sleeve and having its ends in engagement with the sleeve and a relatively stationary member whereby to tend to rotate the sleeve and the bar, a release and stop finger releasably engaging the stop lug and having a projecting actuator arm, and a pair of adjustably spaced abutments one of which is engageable by said arm at the conclusion of the translatory movement of the bar in one or the other direction for effecting release of said finger to permit the bar to rotate about its axis.

17. In a fur cutting machine, a bar carrying a slender flat cutting element having a penetrating point, means for supporting the bar for reciprocation along its axis and for rotation about its axis and for translatory movement back and forth, means for reciprocating the bar, means for effecting the translatory movement, a stop sleeve rotatable with the bar and having a stop lug, a coil spring encircling the sleeve and having its ends in engagement with the sleeve and a relatively stationary member whereby to tend to rotate the sleeve and the bar, a release and stop finger releasably engaging the stop lug, means operable during translatory movement of the bar for releasing said finger to permit the bar to rotate about its axis, and means for retaining a condition of stored tension of the spring.

18. In a fur cutting machine, a bar carrying a slender flat cutting element having a penetrating point, means for supporting the bar for reciprocation along its axis and for rotation about its axis and for translatory movement back and forth, means for reciprocating the bar, means for effecting the translatory movement, a stop sleeve rotatable with the bar and having a pair of diametrically oppositely disposed stop lugs, a coil spring encircling the sleeve and having its ends in engagement with the sleeve and a relatively stationary member whereby to tend to rotate the sleeve and the bar, a shiftable member having release and stop fingers projecting therefrom in 90° angular spaced relation and alternately engageable with the sleeve lugs for the purpose of releasing the sleeve to permit the bar to rotate about its axis and for stopping such rotation after it has proceeded 90°, and means operable during translatory movement of the bar for shifting said shiftable member.

19. In a fur cutting machine, a bar carrying a slender flat cutting element having a penetrating point, means for supporting the bar for reciprocation along its axis and for rotation about its axis and for translatory movement back and forth, means for reciprocating the bar, means for effecting the translatory movement, a stop sleeve rotatable with the bar and having a pair of diametrically oppositely disposed stop lugs, a coil spring encircling the sleeve and having its ends in engagement with the sleeve and a relatively stationary member whereby to tend to rotate the sleeve and the bar, a shiftable member having release and stop fingers projecting therefrom in 90° angular spaced relation and alternately engageable with the sleeve lugs for the purpose of releasing the sleeve to permit the bar to rotate about its axis and for stopping such rotation after it has proceeded 90°, means operable during translatory movement of the bar for shifting said shiftable member, and means for retaining a condition of stored tension of the spring.

20. In a fur cutting machine, a bar carrying a slender flat cutting element having a penetrating point, means for supporting the bar for reciprocation along its axis and for rotation about its axis and for translatory movement back and forth, means for reciprocating the bar, means for effecting the translatory movement, a stop sleeve rotatable with the bar and having a pair of diametrically oppositely disposed stop lugs, a coil spring encircling the sleeve and having its ends in engagement with the sleeve and a relatively stationary member whereby to tend to rotate the sleeve and the bar, a shiftable member having release and stop fingers projecting therefrom in 90° angular spaced relation and alternately engageable with the sleeve lugs for the purpose of releasing the sleeve to permit the bar to rotate about its axis and for stopping such rotation after it has proceeded 90°, and a shifter arm whereby shifting of the shiftable member may be effected, and a pair of adjustably spaced abutments one of which is engageable by said arm at the conclusion of the translatory movement of the bar in one or the other direction for shifting said shiftable member.

21. In a fur cutting machine, the combination of a reciprocating narrow flat cutting element having two cutting edges merging in a central penetrating point, means to bring about relative movement between a hide and said element to cause the individual narrow cuts formed by the element to conjointly form a continuous line cut, and means for turning the element about its axis to cause first one then the other of its cutting edges to be effective in forming said line cut.

22. In a fur cutting machine, the combination of a reciprocating narrow flat cutting element having two cutting edges merging in a central penetrating point, means to bring about relative movement between a hide and said element to cause the individual narrow cuts formed by the element to conjointly form a continuous zig-zag or notched-line cut, and means for turning the element about its axis just prior to the starting of the succession of cuts which conjointly form each zig or zag of the line cut for properly alining the flat of the element with the particular zig or zag next to be made and for causing first one then the other of the edges of the cutting element to be effective in forming said line cut.

23. In a fur cutting machine, a bar carrying a slender flat cutting element having a penetrating point, means for supporting the bar for

reciprocation along its axis and for rotation about its axis and for translatory movement back and forth, means for reciprocating the bar, means for effecting the translatory movement, a stop sleeve rotatable with the bar and having a stop lug, a ratchet collar rotatable on the sleeve, a coil spring encircling the sleeve and having its ends in engagement with the sleeve and the ratchet collar whereby to tend to rotate the sleeve and the bar, a release and stop finger releasably engaging the stop lug, means operable during translatory movement of the bar for releasing said finger to permit the bar to rotate about its axis, and means for rotating the ratchet collar to retain tension in the spring.

24. In a fur cutting machine, a bar carrying a slender flat cutting element having a penetrating point, means for supporting the bar for reciprocation along its axis and for rotation about its axis and for translatory movement back and forth, means for reciprocating the bar, means for effecting the translatory movement, a stop sleeve rotatable with the bar and having a stop lug, a ratchet collar rotatable on the sleeve, a coil spring encircling the sleeve and having its ends in engagement with the sleeve and the ratchet collar whereby to tend to rotate the sleeve and the bar, a release and stop finger releasably engaging the stop lug, means operable during translatory movement of the bar for releasing said finger to permit the bar to rotate about its axis, and a pair of oppositely directed actuating members engageable with opposite sides of the ratchet collar as it moves back and forth between them during translatory movement of the bar and serving to rotate said collar and retain tension in the spring.

25. In a fur cutting machine, a bar carrying a slender flat cutting element having a penetrating point, means for supporting the bar for reciprocation along its axis and for rotation about its axis and for translatory movement back and forth, means for reciprocating the bar, means for effecting the translatory movement, a stop sleeve rotatable with the bar and having a stop lug, a ratchet collar rotatable on the sleeve, a coil spring encircling the sleeve and having its ends in engagement with the sleeve and the ratchet collar whereby to tend to rotate the sleeve and the bar, a shiftable member having release and stop fingers engageable with the sleeve lug for releasing said lug to permit rotation of the sleeve and for engaging said lug for terminating said rotation and including a shifter arm whereby the shifting of said member may be effected, a pair of adjustably spaced abutments one of which is engageable by said arm at the conclusion of the translatory movement of the bar in one or the other direction for shifting said member, and a pair of oppositely directed actuating members engageable with opposite sides of the ratchet collar as it moves back and forth between them during translatory movement of the bar and serving to rotate said collar and retain tension in the spring.

26. In a fur cutting machine, a bar carrying a slender flat cutting element having a penetrating point, means for supporting the element for reciprocation along its axis and for rotation about its axis and for translatory movement back and forth, means for reciprocating the element, means for effecting the translatory movement, a stop sleeve rotatable with the bar and having a pair of diametrically oppositely disposed stop lugs, a ratchet collar rotatable on the sleeve, a

coil spring encircling the sleeve and having its ends in engagement with the sleeve and the ratchet collar whereby to tend to rotate the sleeve and the bar, a shiftable member having 5 release and stop fingers projecting therefrom in 90° angular relation and alternately engageable with the sleeve lugs for the purpose of releasing the sleeve to permit the bar to rotate about its axis and for stopping such rotation after it has 10 proceeded 90°, a shifter arm whereby shifting of the shiftable member may be effected, a pair of adjustably spaced abutments one of which is engageable by said arm at the conclusion of the 15 translatory movement of the bar in one or the other direction for shifting said shiftable member, and means for rotating the ratchet collar step-by-step to retain tension in the spring.

27. In a fur cutting machine, a bar carrying a slender flat cutting element having a penetrating point, means for supporting the element for reciprocation along its axis and for rotation about its axis and for translatory movement back and forth, means for reciprocating the element, 20 means for effecting the translatory movement, a stop sleeve rotatable with the bar and having a pair of diametrically oppositely disposed stop lugs, a ratchet collar rotatable on the sleeve, a coil spring encircling the sleeve and having its 25 ends in engagement with the sleeve and the ratchet collar whereby to tend to rotate the sleeve and the bar, a shiftable member having release and stop fingers projecting therefrom in 90° angular relation and alternately engageable with the sleeve lugs for the purpose of releasing the 30 sleeve to permit the bar to rotate about its axis and for stopping such rotation after it has proceeded 90°, a shifter arm whereby shifting of the shiftable member may be effected, a pair of adjustably spaced abutments one of which is engageable by said arm at the conclusion of the 35 translatory movement of the bar in one or the other direction for shifting said shiftable member, and a pair of oppositely directed actuating members engageable with opposite sides of the ratchet collar as it moves back and forth between them during translatory movement of the bar.

28. In a fur cutting machine, a frame, a bar mounted for reciprocatory and translatory movement having a chuck for removably receiving a slender flat cutting element having a penetrating point, means for reciprocating the bar, means for effecting the translatory movement, a stop sleeve rotatable with the bar and having a stop lug, a coil spring encircling the sleeve and having its ends in engagement with the sleeve and a relatively stationary member whereby to tend to rotate the sleeve and the bar, a release and stop finger releasably engaging the stop lug, and means operable during translatory movement of the bar for releasing said finger to permit the bar to rotate about its axis, said bar having a portion extending without the confines of the frame to permit hand manipulation.

29. In a fur notching machine, a frame, a carriage slidably mounted in the frame, a bar carrying a slender hide cutting element reciprocably supported on the carriage for movement at right angles to the sliding movement of the carriage, a longitudinally extensible bar reciprocating shaft journaled in part in the carriage, reciprocating means connecting said shaft and said bar, means for rotating the shaft, means for reciprocating the carriage, and hide advancing means for moving the hide at right angles both to the direction 5 of reciprocation of the carriage and the direction of reciprocation of the bar.

30. In a fur notching machine, a frame, a carriage slidably mounted in the frame, a bar carrying a slender hide cutting element reciprocably supported on the carriage for movement at right angles to the sliding movement of the carriage, a longitudinally extensible bar reciprocating shaft journaled in part in the carriage, reciprocating means connecting said shaft and said bar, 10 means for rotating the shaft, means for reciprocating the carriage including a crown cam and a follower projecting from the carriage and engaging the cam, braking devices for preventing accelerated movement of the cam or carriage as the follower passes over a high point of the cam, and hide advancing means for moving the hide at right angles both to the direction of reciprocation of the carriage and the direction of reciprocation of the bar.

31. In a fur notching machine, a frame, a carriage slidably mounted in the frame, a bar carrying a slender hide cutting element reciprocably supported on the carriage for movement at right angles to the sliding movement of the carriage, a longitudinally extensible bar reciprocating shaft journaled in part in the carriage, reciprocating means connecting said shaft and said bar, means for rotating the shaft, means for reciprocating the carriage including a crown cam and a follower projecting from the carriage and engaging the cam, braking devices for governing rotation of the cam and including means for increasing the braking action each time the follower passes over a high point of the cam to prevent accelerated movement of the cam or carriage at that interval, and hide advancing means for moving the hide at right angles both to the direction of reciprocation of the carriage and the direction of reciprocation of the bar.

32. In a fur notching machine, a frame, a carriage slidably mounted in the frame, a bar carrying a slender hide cutting element reciprocably supported on the carriage for movement at right angles to the sliding movement of the carriage, a longitudinally extensible bar reciprocating shaft journaled in part in the carriage, reciprocating means connecting said shaft and said bar, means for rotating the shaft means for reciprocating the carriage including a crown cam rotatably surrounding said shaft and a complementary cam portion extending from the end of the carriage and engageable with the cam, and hide advancing means for moving the hide at right angles both to the direction of reciprocation of the carriage and the direction of reciprocation of the bar.

33. In a fur notching machine, a frame, a carriage slidably mounted in the frame, a bar carrying a slender hide cutting element reciprocably supported on the carriage for movement at right angles to the sliding movement of the carriage, a longitudinally extensible bar reciprocating shaft journaled in part in the carriage, reciprocating means connecting said shaft and said bar, means for rotating the shaft means for reciprocating the carriage including a crown cam rotatably surrounding said shaft and a complementary cam portion extending from the end of the carriage and engageable with the cam, hide advancing means for moving the hide at right angles both to the direction of reciprocation of the carriage and the direction of reciprocation of the bar, and means driven from said shaft for imparting slow

movement to said cam and said hide advancing means in constant timed relation.

34. In a fur notching machine, a frame, a carriage slidably mounted in the frame, a bar carrying a slender hide cutting element reciprocably supported on the carriage for movement at right angles to the sliding movement of the carriage, a longitudinally extensible bar reciprocating shaft journaled in part in the carriage, reciprocating means connecting said shaft and said bar, means for rotating the shaft means for reciprocating the carriage including a crown cam rotatably surrounding said shaft and a complementary cam portion extending from the end of the carriage and engageable with the cam, braking devices for preventing accelerated movement of the cam or carriage as the cam and carriage cam portion pass high point engagement, and hide advancing means for moving the hide at right angles both to the direction of reciprocation of the carriage and the direction of reciprocation of the bar.
35. In a fur notching machine, a frame, a carriage slidably mounted in the frame, a bar carrying a slender hide cutting element reciprocably supported on the carriage for movement at right angles to the sliding movement of the carriage, a longitudinally extensible bar reciprocating shaft journaled in part in the carriage, reciprocating means connecting said shaft and said bar, means for rotating the shaft means for reciprocating the carriage including a crown cam rotatably surrounding said shaft and a complementary cam portion extending from the end of the carriage and engageable with the cam, braking devices for governing rotation of the cam and including means for increasing the braking action each time the cam and carriage cam portion pass high point engagement to prevent accelerated movement of the cam or cam portion at that interval, and hide advancing means for moving the hide at

right angles both to the direction of reciprocation of the carriage and the direction of reciprocation of the bar.

36. In a machine for cutting fur bearing hide, the combination of a narrow flat reciprocable cutting element having a cutting edge and a penetrating point, means for supporting the hide with the flesh side toward the cutting element and the hairs thereof depending for free deflection, means to reciprocate the element to cause it to repeatedly penetrate the hide along the desired line of cut with the flat thereof always presented in the line of cut whereby the individual penetrations will enter between the hairs deflecting but not cutting them and conjointly form a continuous smooth edged line cut, and means for shifting the relative positions of the hide and the reciprocating cutting element to cause the line cut to follow a zig-zag path.

37. In a fur notching machine, the combination of hide advancing means, a reciprocable narrow flat cutting element having a cutting edge and a penetrating point and disposed with the flat thereof presented in angular relation to the direction of advancement of the hide, means for supporting the hide with the flesh side toward the cutting element and the hairs thereof depending for free deflection, means to reciprocate the cutting element to cause it to repeatedly penetrate the hide between the hairs thereof deflecting but not cutting them, means to impart translatory movement to the element back and forth across the path of advancement of the hide, and means actuated by movement of said element translating means for altering the angular relation of the element at the conclusion of each back and forth movement thereof to align the flat thereof with the succession of cuts next to be made.

OSCAR M. DEAN. 40
